UNITED STATES PATENT OFFICE

ALFRED VANG, OF DETROIT, MICHIGAN, ASSIGNOR, BY MESNE ASSIGNMENTS, TO MOTOR DEVELOPMENT CORPORATION, A CORPORATION OF MICHIGAN

INTERNAL COMBUSTION ENGINE

Application filed September 27, 1929. Serial No. 395,673.

This invention relates to an internal combustion engine and particularly to an internal combustion engine that is adapted for use in airplanes.

5 It is a well known fact that one of the great desideratums for an airplane engine is dependability of performance. It is one of the objects of this invention to produce an airplane engine that is not only efficient in action, but that is dependable in operation, and this has been achieved by constructing the engine out of a minimum of parts. It is obvious that the fewer the parts in an engine, the less chance there is for an engine breaking 10 down while in operation.

To achieve this dependability of performance there has been produced an internal combustion engine using slide valves. It is appreciated that internal combustion engines 20 utilizing slide valves are not broadly new, and it is equally well appreciated that various defects in the slide valve type of engine have prevented it from becoming extensively used. One of the defects in the slide valve type of engine has been that the valves warp, owing to expansion caused by the heat of combustion and this results in excessive friction between the slide valve and its guide and also in the loss of compression. To eliminate this 30 warping, it is the object of this invention to produce a slide valve of the plate type provided with at least one longitudinal strengthening rib.

Another defect in the slide valve motor has 35 been the loss of compression owing to the inefficiency of the means used for sealing the area immediately adjacent the cylinder ports. It is the further object of this invention to produce a compression sealing means of such 40 a nature that a substantially air tight seal will be at all times maintained between the slide valve and the cylinder port.

It is also an object of this invention to 45 efficiently lubricate the engine by pressure without the heretofore necessary oil pump and this has been achieved by utilizing the slide valves themselves and associated parts as oil pumps.

50 It is also an object of this invention to properly maintain a thin film of lubricant be-

tween the inner face of the slide valve and the guide face adjacent the cylinder wall and yet at the same time to feed this surface by means of oil conduits positioned in the coolest, i. e., the outer surface of the valve 55 which effectively prevents the overheating or destruction of the oil which is used to effect the aforesaid film of lubricant.

It is appreciated that during the compression and explosion following ignition of the 60 compressed gases that the slide valve is subjected to great pressure. Owing to this great pressure to which the valve is subjected at this time, it has been found that any movement of the valve while subjected to this pressure will cause the lubricant to burn and gum 65 up the guide surface of the valve and guide, which renders the engine very inefficient and practically inoperative. To obviate this difficulty it is the object of this invention to produce an internal combustion engine of the 70 slide valve type in which the slide valve remains stationary during the compression and power strokes of the piston, therefore gumming up or destruction of the valve lubricant 75 is obviated. Other objects will appear as the description proceeds.

In the drawings:

Fig. 1 is a vertical section through the 80 engine.

Fig. 2 is a longitudinal vertical section 85 through the engine.

Fig. 3 is a side elevation showing the location of the pressure tank and lubricant feed lines.

Fig. 4 is an elevation of the compression plate.

Fig. 5 is a section along line 5—5 of Fig. 4.

Fig. 6 is a front elevation of the slide valve.

Fig. 7 is a side elevation of the slide valve.

Fig. 8 is a top elevation of the slide valve.

Fig. 9 is a bottom plan view of the slide valve push-rod guide and slide valve guide closing member.

Fig. 10 is a section along the line 10—10 of Fig. 9.

Fig. 11 is an elevation of the positive cam for causing the slide valve to alternately move and remain stationary.

Fig. 12 is a section along the line 12—12 of Fig. 11.

Fig. 13 is an exaggerated view showing the clearance between the valve and the valve 5 guide and the cover plate.

Referring more particularly to the drawings in which there is shown for purposes of description a two-cylinder engine, although it is understood that the engine may 10 be of any specified number of cylinders, the cylinders are generally designated 1. The cylinder consists of a base portion 2 and a cylinder head 3 which is arranged to be threaded or otherwise suitably secured to the 15 base 2 as at 4.

The cylinder 1 is provided with a suitable piston 5 which is connected to the crank shaft 6 by a suitable connecting rod 7. A suitable crank case 8 is secured to the cylinders 1 by any suitable means such as the 20 bolts 9.

Inasmuch as the cylinders are similar in all respects, the description will be limited to one of the cylinders and will be equally applicable to the remaining cylinders.

The cylinder 1 and the cylinder head 3 are arranged to be air cooled and to better effect this air cooling, are provided with the fins 10.

30 The head 3 is preferably an integral casting and comprises the cylinder portion 11 (Fig. 1) provided with the intake port 12, the exhaust port 13 and also the two slide valve guide portions generally designated 14 and 15.

35 Inasmuch as the slide valve guide portions 14 and 15 are identical, the description will be directed to one of the slide valve guide portions and will be considered as equally applicable to the other slide valve 40 guide. The slide valve guide is provided with a suitable cover member 16 which is secured to the guide by any suitable means such as bolts 17.

45 In Fig. 3 the valve guides are shown at the left with the cover 16 in position, and at the right with the guide cover removed. It will be seen that the valve guide 14 is provided with suitable longitudinal grooves 18 and with a recessed portion 19. The recessed 50 portion 19 is provided with a plurality of endless grooves 20 which surround the exhaust port 13. The recessed portion 19 is arranged to receive a compression plate 25 (Fig. 4) which is here shown as being rectangular and provided with an opening 29 which is 55 co-extensive with the exhaust port 13. The compression plate 25 is provided with a plurality of endless raised ribs 26 which surround the opening 29. The plate 25 is arranged to be seated in the compression plate seat 19 so that the projected ribs 26 slidably engage and nicely fit within the endless grooves 20 and in this position the opening 29 coincides with the exhaust port 13. The 60 projected ribs 26 are arranged to have a very

limited clearance in the endless grooves 20 in which they slidably fit and in conjunction with the very thin film of lubricant provide a substantially gas-tight seal between the exhaust port 13 and the surface area of the 70 slide valve guide 14 immediately surrounding the exhaust port.

Owing to the heat created by the machining of the metal from which the slide valve is fabricated and owing to the heat of combustion, the slide valves heretofore used have warped and become ineffective. To overcome this defect there is here provided a slide valve 30 which is substantially U-shaped in cross section (Fig. 8) and consists of the flat surface portion 31 and the longitudinal flanges 32 which re-enforce the valve and prevent warping. The valve 30 is provided with a port 33 co-extensive in size with the cross sectional area of the exhaust port 13. The valve 30 is arranged to be assembled in 80 slide relation upon the valve guide 14 with the flanges 32 projected inwardly toward the inside of the cylinder and slidably engaging the guide 14 in the longitudinal grooves 18. It will be noted that the inner face 33 of the valve slidably engages the outer face 34 of the compression plate 25 but a very small clearance as at 35 permits a sloppy fit.

The front face 37 of the valve 30 is provided on each side with the grooves 38 which extend vertically downward approximately intermediate the length of the valve and then extend laterally inwardly and downwardly as at 39. In substantially equidistantly spaced relations are the holes 40 projecting from the bottom of the grooves 39 inwardly and completely through the slide valve 30.

The slide valve is arranged to reciprocate upwardly and downwardly upon the guide 14, and to this end is provided with a push rod 80. The push rod 80 projects through and slidably engages the closure plate 41 which closes the valve chamber 42 which is formed cooperatively by the recesses in the lower portions of the valve guide cover 16 and valve guide 14. The end of the push rod 80 which projects through the closure plate 41 has a recessed fit as at 43 with the lower end of the valve 30 and is secured thereto by the screw 44.

The lower end of the push rod 80 is arranged to be guided by a suitable guide 45 and carries at the lower end a roller 46 mounted upon the pin 47.

The cam member is shown in detail in Fig. 11 and may be generally designated 50. The cam 50 is arranged to be mounted upon a suitable cam shaft 51, and is provided with peripheral flange 52 and a flange 53 concentric with the flange 52 and positioned inwardly from the flange 52. The flanges 52 and 53 constitute a race for the roller 46. As stated above the cam member is arranged to maintain the slide valve in stationary position dur-

ing the compression and power strokes of the piston, and to achieve this the cam has a definite predetermined configuration. The center of rotation may be designated 54 and as viewed in Figure 11 the flanges 53 and 52 below the line A—A are a true circuit concentric with, and having the point 54 as a center of rotation. The flanges 52 and 53 are symmetrical and considering 54 the center of rotation, the radius of the flanges 52 and 53 gradually increase from the line A—A upwardly till they achieve their greatest length at the top of the cam which may be designated B. The difference in length between the radii 54—A and 54—B is arranged to be not less than the height of the exhaust port 13 and is preferably slightly greater than the height of the exhaust port 13 to permit the valve to overlap the cylinder ports when closed.

The cam shaft 51 has a reduction gear connection with the crank shaft 6 of a two to one ratio; that is, the crank shaft makes two complete revolutions to each single revolution of the cam shaft. The cylinder head 3 has mounted therein a suitable spark plug 56 located in the uppermost portion of the cylinder head. Any well known timing device may be used to properly time the sparking of the spark plug. The timing device is suitably synchronized with the cams so that the fire and the resultant explosion occurs while the roller 46 is upon that part of its course below the line A—A, that is, while the roller 46 travels the course A—A the valve remains closed and stationary.

The engine is arranged to be fed by force or pressure feed lubrication and to this end the slide valves are used in conjunction with their guides and associated parts as pumps. The guides 14 in conjunction with the cover plate 16 form a chamber 60 above the slide valve 30 (Fig. 1). The cover plate 16 is mounted upon the guide 14 with a gas tight seal and the upper end of the cover plate 16 is provided with an intake port 61 and an exhaust port 62 which communicate with chamber 60. The ports 61 and 62 are each provided with a suitable check valve such as that constituted by the ball 63 held against the valve seat 64 by the valve spring 65. The check valves governing the ports 61 and 62 are the reverse of one another. The ports are connected to a suitable oil feed and pressure tank 66 by means of the feed line 67 and exhaust line 68. The pressure tank 66 is provided with a suitable relief valve 69 which is arranged to exhaust the pressure in the oil tank 66 over the amount of pressure desirable in the tank. It will be readily seen that the slide valve 30 serves as a plunger arranged to draw in the lubricant from the tank 66 through the feed line 67 and check valve 61 into the chamber 60 on the downstroke. Upon the upward stroke of

valve 30 any surplus oil or air is discharged through the exhaust port 62 and associated oil line 68 which conveys it back to the pressure tank 66. It is understood that the size of the intake port 61 and exhaust port 62 ⁷³ can be adjusted to admit and exhaust any desirable amount of oil during operation.

Since the compression plate 25 can move outwardly and inwardly without decreasing its sealing effect, it is possible to permit the slide valves to have a sloppy fit in the guides and this prevents any gumming up of the guides and valves by the lubricant. This sloppy fit of the slide valve 30 has been nicely brought out in the exaggerated view (Fig. 13). It will be seen that the opening between the valve guide 14 and the cover plate 16 is sufficiently greater than the thickness of the valve 30 to permit the clearance 70. This clearance is preferably in the neighborhood of .015 of an inch although it can be increased or decreased and yet an effective seal be maintained between the valve and the compression plate 25 to in turn seal the port 13. The point is that the clearance 70 can not be decreased sufficiently to effectively prevent loss of compression without causing the oil to gum and the valve to stick in the valve guide, hence, owing to the sealing action of the compression plate 25, this sloppy fit or large clearance of the valve 30 in the valve guides is permissible to obviate gumming of the oil and sticking of the valve without loss of compression which would obviously occur if the compression plate 25 ⁸⁵ were omitted.

In operation during the compression and the explosion of the gases in the combustion chamber the compression plates 25 will be forced outwardly and tightly against the slide valve 30. This in conjunction with the thin film of oil between the compression plate 25 and the valve 30 will effect a gas tight seal between the two contacting surfaces. When the compression plate 25 is forced slightly outward the endless ribs 26 move slightly outward in the endless grooves 20, but still maintain their gas tight contact with the sides of the grooves 20. The endless grooves 20 and ribs 26 are provided with a very thin film of oil which further insures against loss of gas or compression.

By referring to Fig. 7 it will be seen that the valve 30 has its upper edge chamfered as at 70, hence, upon the oil being pumped into the chamber 60 it flows over the chamfered edge 70 and downwardly along the grooves 38 and then laterally inwardly and downwardly in the grooves 39 from whence it passes inwardly through the holes 40 to lubricate the face 33 of the valve 30 and the guide surface of the guide 14 and the compression plate 25. This feeding arrangement owing to the fact that the grooves 38 ¹²⁰ ¹²⁵ ¹³⁰

are on the outside face of the valve 30 maintains the oil adjacent the cooling fins and the cooling surface of the engine until it has passed through holes 40. This tends to prevent destruction of the oil by overheating.

- 5 It will be noted that the slide valve guide portion 40 is angularly displaced relative to the cylinder 1 so that its only area of contact with the cylinder 1 is immediately adjacent 10 the cylinder port 13. This angular arrangement permits the slide valve and guide and associated parts to be substantially completely surrounded by air for cooling purposes.

- 15 It will be noted that the exhaust port 13 is positioned above the intake port 12. The configuration of the cylinder head is such that in cross-section the approximate half of the cylinder head adjacent the exhaust port 20 is concave and the approximate half adjacent the intake port is convex when viewed from the inside of the cylinder. This curvature of the cylinder head creates a turbulence of the gases during the compression stroke of 25 the piston and firing of the gases which causes a uniform and more efficient combustion.

- The piston is arranged to have a surface that in cross-section is substantially parallel 30 to that of the cylinder head. Owing to the location of the spark plug 56 at the highest point in the combustion chamber the gases are ignited adjacent the higher area of the piston surface and consequently as ignited 35 effect a rolling or oblique blow upon the piston rather than a vertical blow. This rolling blow of the gases upon the piston tends to give a smoother running and less vibratory engine.

- 40 I claim:

1. In an internal combustion engine having a combustion chamber and a port therefor, the combination of a guide having an opening therein substantially coincident with 45 the said port, a valve arranged to slidably engage the said guide with a sloppy fit for opening and closing the said port, a cover plate secured to the said guide surface for the said slide valve, and a compression plate 50 directly engaging the said valve having an opening therein substantially coincident with the port and an endless ridge extending around the said opening, the said guide surface having a complementary groove about 55 the said opening, the said endless ridge of the compression plate arranged to have a sliding engagement with the groove in the said guide, whereby the compression plate can move outwardly during the compression and power 60 strokes to effect a substantially air tight seal between the cylinder port and the said slide valve.

2. In an internal combustion engine having a combustion chamber and a port therefor, the combination of a slide valve arranged 65

to be actuated to open and close said port, a guide for said valve having an endless groove surrounding said port, the valve having a sloppy fit with the said guide, and a single sealing means surrounding said port having 70 an endless ridge to slidably engage in said groove and a surface slidably engaging said valve whereby the valve is sealed against compression loss.

3. In an internal combustion engine having 75 a combustion chamber and a port therefor, the combination of a flat slide valve arranged to be actuated to open and close said port, a flat guide for said valve having an endless groove surrounding said port, the flat valve having a sloppy fit with the said flat guide, and a single sealing means surrounding said port having an endless ridge to slidably engage in said groove and a surface slidably engaging said valve whereby the valve 80 is sealed against compression loss.

4. In an internal combustion engine having 85 a combustion chamber and a port therefor, the combination of a slide valve arranged to be actuated to open and close said port, a guide surface for said valve having an endless groove around said port, a cover for said guide surface, the said valve arranged to have a sloppy fit between said cover and guide 90 surface, a plate having an opening therethrough and an endless ridge arranged to engage in said groove and a surface arranged to slidably engage said slide valve with a lap fit whereby the said plate adheres to said slide valve and effects a gas tight seal about 95 100 said port.

5. In an internal combustion engine having 105 a combustion chamber and a port therefor, the combination of a flat slide valve arranged to be actuated to open and close said port, a guide including a flat surface for said valve having a recess with an endless groove extending around said port, the said valve having a sloppy fit with said guide, and a flat plate having an endless ridge arranged 110 to slidably fit in said recess with said ridge slidably engaging in said groove and a flat surface having a lap fit with said valve whereby said plate adheres to said valve and effects a gas tight seat about said port. 115

6. In an internal combustion engine having 120 a combustion chamber and a port therefor, the combination of a reciprocating slide valve for opening and closing the said port, a guide for the said valve having an endless groove surrounding the said port, the valve having a sloppy fit with the said guide, and sealing means for surrounding the said port in slid- 125 able engagement with the said valve and having a portion disposed in the said groove, the said sealing means being freely movable inwardly and outwardly in the said groove during the intake and compression strokes of the piston.

7. In an internal combustion engine hav- 130

ing a combustion chamber and a port therefor, the combination of a reciprocating slide valve for opening and closing the said port, a guide for the said valve having an endless groove surrounding the said port, the valve having a sloppy fit with the said guide, and a plate having an endless ridge for sealing the valve against compression loss, the said plate yieldably engaging the said valve and the endless ridge having a freely sliding engagement inwardly and outwardly with the endless groove during the intake and compression strokes of the said piston.

8. In an internal combustion engine having a combustion chamber and a port therefor, the combination of a slide valve arranged to be actuated to open and close the said port, a guide for the said valve having an endless groove surrounding the said port, the said valve having a sloppy fit with and adapted to directly engage the said guide, and sealing means comprising a plate having a flat surface slidably engaging said valve and an opening substantially coincident with the port, and an integral ring adapted to slidably engage in the said endless groove surrounding the said port whereby the valve is sealed against compression loss.

In testimony whereof I affix my signature.

ALFRED VANG.
